UNITED STATES PATENT OFFICE.

HENRY H. HARRISON, OF NEW YORK, N. Y., AND FREDERICK C. BUFFUM, OF STANTON, FLORIDA.

HECTOGRAPH PRINTING-PRESS.

SPECIFICATION forming part of Letters Patent No. 427,077, dated May 6, 1890.

Application filed February 12, 1889. Serial No. 299,614. (No model.)

To all whom it may concern:

Be it known that we, HENRY H. HARRISON, of the city, county, and State of New York, and FREDERICK C. BUFFUM, of Stanton, in the county of Marion and State of Florida, have invented a new and Improved Hectograph Printing-Press, of which the following is a full, clear, and exact description.

Reference is to be had to the accompanying drawings, forming a part of this specification, in which similar letters of reference indicate corresponding parts in all the figures.

Figure 1 is a broken plan view of our invention. Fig. 2 is a broken front elevation. Fig. 3 is a side elevation. Fig. 4 shows a modified form of mutilated cam and gear wheel. Fig. 5 is a central sectional elevation taken on the line $x-x$ of Fig. 1. Fig. 6 is a detailed view of the drawing-rollers and a portion of the gearing for operating the same, and Fig. 7 is a transverse sectional view of the same on line $y-y$ of Fig. 6.

The invention will first be described in connection with the drawings, and then pointed out in the claims.

Securely attached to the base A are the side housing-frames B B', braced at the top by the tie-rod C.

D is the impression-cylinder, made, preferably, of wood, provided at one end with the two gear-wheels D' D'', the latter of greater diameter than the former, and pivoted in suitable bearings in the side frames B B'. The gear-wheel D'' meshes with the gear-wheel E' on the end of the printing or copying roller E, which rests on the impression-cylinder D and is held in open bearings, in this instance the half-bearings f made a part of the pivoted arm F. A spring f' acts upon each arm F between it and a screw f'', by which the pressure may be regulated.

G represents the hectograph material applied to a cylinder or sleeve G', of tin or other thin substance, placed loosely on the roller E, as shown clearly in Fig. 5. The upper rim of each of the side frames B B' is formed with a passage B³, through which the ends of the shaft of the roller E may be passed, thus allowing said cylinder to be removed from the machine, so that the shell or sleeve G',

with its hectographic material, may be removed and another put in its place and the whole easily returned to position in the machine. In this manner—that is, by adapting the roller E to be removed and by employing the sleeve G', on which the hectographic material is placed—the supplying of the machine with new copying-cylinders is a matter of very small expense and trouble.

In order to prevent the hectographic material from slipping endwise on the sleeve G, we wrap the sleeve with wire or cord G², as shown clearly in Fig. 1; but this may be omitted or other means substituted.

In front of the rollers D E are placed the drawing-rollers H H' on shafts J J', respectively. These rollers serve to draw the paper K from the reel L through between the printing-rollers, and also to prevent the paper from adhering to the hectographic material. Motion is imparted to the rollers H H' from the gear-wheel D' on the impression-cylinder, the same meshing with the pinion M' on the shaft M. The shafts J J' are geared together by the pinions J² J³, and a pinion M² on shaft M meshes with the pinion J³, as shown clearly in Figs. 6 and 7, so that when cylinder D is revolved by turning the crank N the rollers H H' will be revolved in the same direction as the printing-cylinders.

O (see Fig. 5) is a small depressing rod or roller placed back of the drawing-roller H' in the angle formed by the contiguous surfaces of the rollers D H'. The paper as it issues from the printing-surfaces passes down under this rod or roller O, as shown in Fig. 5, so that the paper will be detached from the hectographic material as soon as the impression is made.

As the paper issues from the machine it is cut by shears composed of the stationary blade P and the pivoted blade P'. This latter blade is formed with the extension P², to which downward and laterally acting springs P³ are attached for normally holding the shears open and forcing the cutting part of the blade P' toward the stationary blade, so that there will be no failure when blade P' is closed in cutting the paper. The said blade P' is operated by the centrally-pivoted double

crank or lever Q, one arm q of which reaches under the extension P^2 of the blade P', the other arm q' reaching back in the orbit or range of the curved flange or cam s on the 5 mutilated gear-wheel S, which cam operates to depress the arm q' of the said lever, which elevates the arm q , which in turn throws down the blade P' of the shears and cuts the paper.

The mutilated gear-wheel S is journaled on 10 the gudgeon S', attached to the side frame B' and by its cog-teeth s', meshing with the pinion T on the shaft of the impression-cylinder D, imparts intermittent motion to the whole machine, the printing or copying mechanism 15 remaining at rest while the cutting is performed.

The printing mechanism is locked in dormant position by the pawl U, adapted to engage with the pinion T, and this pawl immediately after the cutting is effected is lifted out of engagement of the pinion T by a stud s² on the gear S. (Shown clearly in Fig. 3.)

In doing rapid work, in place of the single-acting wheel S (shown in Fig. 3) we shall use 25 the double-acting wheel shown in Fig. 4, formed with two sets of gear-teeth s', two cam-flanges s, and two studs s², so that two impressions will be taken at each revolution of the wheel, and likewise two operations of the 30 shears.

The reel L, to hold the roll K of paper, comprises on one side the rod L', held in a sleeve l on the side frame B', in which sleeve it may be adjusted and secured by the set-screw l'. 35

The rod L' carries the flange L² and the cone L³, which latter enters the end of the roll, as shown clearly in Fig. 1. On the opposite side the reel is composed of the rod V, flange V', and cone V². The rod V is placed loosely in 40 a tube or socket V³, held in the sleeve v of the side frame B, in which the said socket may be adjusted to suit paper of different widths, the sleeve being provided with a set-

screw v' for fastening the said sleeve at any desired position. In the sleeve V³ is placed 45 the coiled spring W, which acts on the rod V, forcing it outward to press on the roll K to produce the required tension. The pressure of the spring W may be regulated by the screw-rod W' engaging a screw-threaded aperture 50 in the inner end of the rod V and the jam-nut w placed on the rod outside of the sleeve V³. The rod W' also serves as a means to withdraw the cone V² to insert or remove a 55 roll of paper.

Having thus described our invention, what we claim as new, and desire to secure by Letters Patent, is—

1. The impression-cylinder D and printing-roller E, having the hectographic material C 60 surrounding the same, in combination with the shears P P', the drawing-rollers H H', located with their meeting surfaces in line with the contact-point of the impression-cylinder and printing-roller and between the same and 65 the said shears, and the rod O, placed in the space between the adjacent surfaces of the impression-cylinder and the roller H' and below the point of contact between the impression-cylinder and the printing-roller and below the point of contact between the drawing- 70 rollers, substantially as described.

2. The hollow cylinder G', of tin or other material, wrapped with wire or cord G² and having the hectographic material G applied 75 to its outer surface and placed loosely upon the roller E, substantially as and for the purposes set forth.

HENRY H. HARRISON.

FREDERICK C. BUFFUM.
